UNITED STATES PATENT OFFICE.

BENJAMIN H. M. SPARGO, OF HAWKS BURN, MELBOURNE, VICTORIA, AUSTRALIA.

ALARM.

1,311,424.

Specification of Letters Patent. Patented July 29, 1919.

Application filed October 16, 1918. Serial No. 258,375.

To all whom it may concern:

Be it known that I, BENJAMIN H. M. SPARGO, a subject of the King of Great Britain, residing at 18 Howitt street, Hawksburn, Melbourne, Victoria, Australia, have invented certain new and useful Improvements in Alarms, of which the following is a specification.

The invention relates to alarms and more particularly to means whereby an alarm may be sounded at a given point at any predetermined time, the purpose being to provide novel means whereby the alarm may be set and the duration of operation regulated.

15 The invention has for its object to combine with a clock or like time movement, electric means including a bell or like signal and adjustable contacts whereby the circuit may be closed at a given time and the period 20 of closing such circuit regulated so that the bell or alarm may sound for a given time, thereby insuring ample warning being given.

The invention has for its object to devise 25 novel contact means that are adjustable about the dial and adjustable radially so as to present more or less extent of surface whereby the period of sounding of the alarm may be regulated to meet requirements.

30 The drawing illustrates a preferred embodiment of the invention. However, it is to be understood that in adapting the same to meet different conditions, various changes in the form, proportion, and minor details of 35 construction may be resorted to without departing from the nature of the invention as claimed hereinafter.

In the drawings:

Figure 1 is a detail view showing the 40 application of the invention.

Fig. 2 is a sectional detail through a portion of the dial illustrating the relation of the hands and coöperating contacts.

Fig. 3 is a perspective view of one of the 45 adjustable contacts.

Fig. 4 is a section on the lines 4—4 of Fig. 3 looking in the direction of the arrow.

Corresponding and like parts in the several views of the drawing are referred to in 50 the following description and indicated in the several views of the drawing by like reference characters.

In carrying out the invention, the clock or time movement of any make or design is 55 utilized, the same being provided with a ring 1 which is disposed concentric with the

dial 2. The ring 1 may be mounted in any manner and provides supporting means for any number of adjustable contacts A. The clock or time movement is provided with the 60 usual minute hand 3 and hour hand 4. The hour hand 4 is electrically insulated from the frame of the clock and is included in the alarm circuit and coöperative with the contacts A to close the circuit at a predetermined time and sound the alarm. 65

The alarm circuit is indicated at B and comprises a battery 5 and a bell or like alarm device 6. One terminal of the wire comprising the circuit B is attached to the ring 1 or framework of the clock. The other terminal of the wire or circuit B is connected with the hour hand 4 and as stated is electrically insulated so as to prevent short circuiting. The circuit is closed at the predetermined time by the extremity or tip of the hour hand 4 making electrical connection with one of the contacts. 75

As indicated most clearly in Fig. 3, the contacts comprise two members 7 and 8. 80 The member 8 is provided at its outer end with a spring clip 9 which is adapted to make snap engagement with the ring 1 so as to hold the contact in the adjusted position and yet admit of its movement on the ring 85 or its application to or removal therefrom as required. The member 7 is adjustable with reference to the member 8 and its opposite edge portions are bent as indicated at 10 to embrace opposite edge portions of the member 90

8. The bent edge portions 10 are resilient so as to frictionally engage the edge portions of the member 8 and thereby retain the member 7 securely in the adjusted position. The member 7 is radially adjustable so as to be 95 moved outward and thereby admit of the hour hand 4 passing any one of the contacts without engaging the same. The inner end 11 of the adjustable member 7 is made tapering, the purpose being to provide for varying 100 the duration of operation of the alarm. By adjusting the member 7, a portion thereof may be brought into position to be engaged by the tip or contact of the hour hand so that the extent of contact may vary according to 105 the relative position of the member 7. The extremity of the tip or contact of the hour hand 4 travels in a prescribed circle and by adjusting the member 7 in or out the tapered end 11 may be brought to a position to present a greater or less extent of surface to be 110 engaged by the extremity or contact of the

hour hand 4. It is to be remembered that the hour hand travels slowly, the distance between the hour divisions of the dial represent sixty minutes, hence by properly proportioning the member 7 and the tapered end 11 thereof, the alarm may be caused to sound for any determined fractional part of an hour as will be readily understood.

The adjustable member 7 is provided with 10 graduations to facilitate the setting of the member when it is required to adjust the contact. Any one of the circles of the dial may be used as a guide in connection with the graduations on the member 7 when adjusting the contact.

It will be understood that the bell or alarm 6 may be located in a room or at any point and one of the contacts A may be adjusted so as to effect a sounding of the alarm 20 at the given time and have a predetermined period. By providing a number of contacts A, a plurality of circuits may be associated with a single clock and the latter may be utilized for closing the several alarm circuits at the required time.

The foregoing description and the drawings have reference to what may be considered the preferred, or approved form of my invention. It is to be understood that I

may make such changes in construction and arrangement and combination of parts, materials, dimensions, et cetera, as may prove expedient and fall within the scope of the appended claims.

Having thus fully described my invention, 35 what I claim as new and desire to secure by Letters Patent, is:

1. In combination with a clock and an electric alarm including a hand of the clock, a contact having a tapering portion and adjustable to bring a greater or less extent of 40 the contact into the path of the movable contact for regulating the period of the operation of the alarm.

2. In combination with a clock, a ring concentric with the dial thereof, an electric alarm circuit, a contact adjustable on the ring and embodying a radially movable element having a tapered portion to present a greater or less extent of surface for the movable contact, whereby the duration of the 45 alarm may be regulated.

In testimony whereof I affix my signature in presence of two witnesses.

BENJAMIN H. M. SPARGO.
